UNITED STATES PATENT OFFICE.

BASIL RUYSDAEL, OF NEW YORK, N. Y.

COLLAPSIBLE TUBE.

1,125,402.

Specification of Letters Patent.

Patented Jan. 19, 1915.

Application filed April 1, 1912. Serial No. 667,646.

To all whom it may concern:

Be it known that I, BASIL RUYSDAEL, a citizen of the United States of America, residing in New York, in the borough of 5 Manhattan, county and State of New York, have invented certain new and useful Improvements in Collapsible Tubes, of which the following is a specification.

This invention relates to certain improvements in the nipples and caps of collapsible tubes, bottles and similar containers so that the removing and replacing of the cap is facilitated, a tight closure of the tube secured, and a cheapening of the tube or other 15 container obtained; and for this purpose the invention consists of a collapsible tube or other container, provided with a conically-tapering nipple having one or more grooves in its sides, and a cap having an interior recess corresponding in shape with the nipple, and one or more grooves in the lower portion of said recess, as will be fully described hereinafter and finally pointed out in the claims.

25 In the accompanying drawings, Figure 1 represents a perspective view of a collapsible tube with my improved closing device, Fig. 2 is a side-elevation of the tube with the cap removed, Fig. 3 is a vertical transverse section through the nipple and cap, on line 3—3, Fig. 1, drawn on a larger scale, and Fig. 4 is a horizontal section, drawn on line 4—4, Fig. 3.

Similar letters of reference indicate corresponding parts throughout the several figures of the drawings.

Referring to the drawings, *a* represents the body of my improved collapsible tube or other container, *b* the nipple, and *c* the cap 40 of the same. The nipple *b* is made of a conically-tapering exterior shape and provided at one or more points of its upper portion with one or more side-grooves *b'*. The cap *c* is grooved or knurled on its outside and provided with an interior conically-tapering recess which corresponds with the exterior shape of the nipple *b*, said cap being likewise provided with a groove *c'* at one or more points, said groove or grooves being arranged at the lower end of the interior wall of the nozzle, but of sufficient length so that when the cap is placed on the nipple for closing the same the groove or grooves *c'* of the cap extend somewhat over the lower ends of the grooves *b'* of the nipple. The

grooves *b'* and *c'* serve when placed in alignment with each other on placing the cap over the nipple, for giving a certain outlet for the liquid, pasty or other contents of the tube, while still preserving the tight closure 60 of the same, especially immediately after the cap is slightly turned on the nipple so as to place the interior grooves out of register with each other. The interior recess of the cap *c* is made cylindrical at its upper portion *c''* so that when the cap is forcibly pressed downward over the nipple it compresses the upper end of the nipple and produces a perfectly tight and reliable closure 65 of the collapsible tube or other container for 70 the reason that the lower edge of the cylindrical recess *c''* exerts a considerable pressure on the upper edge of the nipple.

The cap is provided at the outside in line with the interior groove with an index-mark *d'* and the top of the tube with a similar mark *d* in line with the groove on the nipple, so that the grooves are readily placed in alignment. A chain connects the cap with the tube for preventing the dropping 80 or loss of the cap.

The tight closing of the nipple is produced by the frictional pressure of the cap on the same. A slight turn of the cap permits the removal of the same from the 85 nipple, or the tight replacing of the same thereon without the loss of time required for unscrewing the cap and removing the same or screwing it on for replacing the same. The cylindrical recess *c''* provides a 90 space within which paint, or other contents of the tube, may accumulate in a wet condition, whereby, when the cap is removed, only fresh paint is exposed at the top of the nipple and expelled when the tube is 95 pressed. In applying the cap to the nipple, the same is applied with the grooves *b'* *c'* in register. Thereby, the surplus material which is always left at the outside of the nipple, and which in the act of applying 100 the cap is caught between the same and the nipple, is forced into the cylindrical recess and into the grooves. The two tapering metal surfaces, namely, that of the cap and that of the nipple, are thus left substantially 105 clean, so that secure frictional contact can take place. The grooves provide an outlet for the surplus material, so that the considerable pressure tending to lift the cap 110 from the nipple, which this surplus material

would otherwise cause, is relieved. The cap is worked from side to side, on the nipple, with the grooves in register, until all the surplus material is squeezed out from between the tapering faces, and the cap is then finally turned sufficiently to place the grooves out of register. In the operation of applying the cap, the surplus material is exuded from the lower groove, and may be wiped off from the top of the tube by cloth or other means. The cylindrical recess, in connection with the grooves, provides a space of large capacity, wherein a considerable quantity of surplus material may be contained under no cap-lifting pressure, whereby the advantages of a fresh paint supply are obtained in a cap secured by friction only.

As the collapsible tubes and similar containers are made of comparatively soft metal, the reliable fitting together of nipple and cap is obtained. At the same time the improved closing device is considerably

cheaper than the screw-threaded nipples and caps heretofore in use. 25

I claim:

A closing device for collapsible tubes and other containers, comprising an outwardly conically-tapering nipple having a longitudinal groove in its outer and upper portion, 30 and a cap having an interior inwardly conically-tapering recess fitting over the nipple and provided with a longitudinal groove in its inner and lower portion, said cap being provided with an interior cylindrical space 35 beyond the outer end of the nipple when seated, an outlet being provided from said cylindrical space when said grooves overlap or register.

In testimony, that I claim the foregoing as my invention, I have signed my name in presence of two subscribing witnesses.

BASIL RUYSDAEL.
